(57) CLAIM

We claim the ornamental design for a carrying case, as shown and described.

DESCRIPTION

FIG. 1 is a frontal perspective view of the present invention. FIG. 2 is a front elevation view of the present invention. FIG. 3 is a rear elevation view of the present invention. FIG. 4 is a top plan view of the present invention. FIG. 5 is a bottom plan view of the present invention. FIG. 6 is a left side view of the present invention; and, FIG. 7 is a right side view of the present invention. The broken line showing of feet in FIGS. 2, 3, 6, and 7 is for illustrative purposes only and forms no part of the claimed design.
